UNITED STATES PATENT OFFICE.

CHARLES W. WEAVER AND ALICE H. WEAVER, OF DENVER, COLORADO; SAID
CHARLES W. WEAVER ASSIGNOR TO SAID ALICE H. WEAVER.

ATTACHMENT FOR SLOP JARS AND THE LIKE.

Application filed February 17, 1922. Serial No. 537,253.

To all whom it may concern:

Be it known that we, CHARLES W. WEAVER and ALICE H. WEAVER, citizens of the United States, residing at the city and county of Denver and State of Colorado, have invented certain new and useful Improvements in Attachments for Slop Jars and the like; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to means to be applied to the covers of slop jars and similar vessels for the purpose of preventing noise and breakage.

It is well known that where slop jars are employed, the noise incident to the removal and the replacement of the cover becomes very noticeable, and where the jar and cover are made of vitreous material, breakage often takes place, owing to the careless application of the cover to the jar. We have also found that where jars and covers of the ordinary construction are used, odors will escape into the room in spite of the cover.

It is the object of this invention to provide a means that can be applied to the cover of a slop jar or similar receptacle for the purpose of preventing the noise and breakage referred to above, and which will also serve as a seal and produce a tighter joint than with the ordinary construction.

In order to more clearly describe our invention, we shall have reference to the attached drawing in which—

Fig. 1 shows a slop jar and cover equipped with our noise preventing means, parts being broken away to show the relation of the parts;

Fig. 2 shows a perspective view of the rubber protective ring; and

Fig. 3 shows a transverse section thereof. The same reference numerals will be used

to designate the same parts throughout the several views.

Numeral 1 represents an ordinary slop jar having a cover 2, to the edge of which our protective and sealing ring 3 has been applied. Our sealing and protecting ring is made of rubber or other suitable material which has a substantially U-shaped cross section which adapts it to be applied to the edge 4 of the cover, in the manner illustrated in Fig. 1. The upper side 5 of the ring is narrower than the lower side 6, as its only function is to hold the ring in place on the cover; however, it may be made as wide as side 6 or wider, if it is found desirable to do so. Side 6 comes in contact with the top of the jar and prevents the cover from producing a noise as it is put in place and removed from the jar. The ring 3, being made from resilient material such as rubber, will adapt itself to any minor irregularities in the surface of the jar and form a seal that will prevent odors from escaping from the jar and entering the room.

In Fig. 2 we have shown a perspective view of our ring 3, and in Fig. 3 a cross section thereof; these figures are plain and need no explanation.

Our ring 3 is made somewhat shorter than the circumference of the cover to which it is to be applied, and requires to be slightly stretched in order to be applied thereto. The tension in the ring serves to hold it in place on the cover.

Although we have shown our protective ring applied to a slop jar, it is evident that it can be used in connection with any similarly constructed vessel where a noiseless operation is desired, or where a better sealing action is wanted.

Having now described our invention, what we claim as new is—

1. In combination, a vessel, a cover adapted to be applied thereto, said cover having an outwardly extending flange adapted to contact with the upper edge of the vessel, a resilient ring U-shaped in cross section applied to said flange and adapted to

separate the lower surface thereof from the upper edge of the vessel, whereby a seal is formed.

2. In combination, a vessel, a cover adapted to be applied thereto, said cover having an outer flange and a ring U-shaped in cross section and composed of flexible yieldable

material applied to said flange to form a seal.

In testimony whereof we affix our signatures.

CHARLES W. WEAVER.
ALICE H. WEAVER.
